UNITED STATES PATENT OFFICE.

EDWARD H. WYMAN, OF AIKEN, SOUTH CAROLINA.

AEROPLANE.

1,128,395.

Specification of Letters Patent. Patented Feb. 16, 1915.

Application filed April 8, 1914. Serial No. 830,398.

To all whom it may concern:

Be it known that I, EDWARD H. WYMAN, a citizen of the United States, residing at Aiken, in the county of Aiken and State of 5 South Carolina, have invented certain new and useful Improvements in Aeroplanes, of which the following is a specification.

This invention relates to aeroplanes and other flying machines which are heavier 10 than air and are sustained by the action of moving planes upon the air.

The invention more particularly relates to devices having special construction and relation to each other, and contrived for the 15 purpose of placing the weight of practically all the heavier bodies carried by the machine below the planes. By such arrangement of the weight a substantial increase of stability is attained, but, the action of the air against 20 the bodies thus carried below the planes tends to turn the planes downwardly in front, and it is also an object of this invention to provide means of particular construction and arrangement enabling the operator 25 to draw the weight carried below the planes, toward the rear, thus, in effect, turning the forward edges of the planes upwardly and counteracting the tendency of the air as above mentioned to incline them 30 downwardly. The same means may be employed to incline the planes upwardly when it is desired that the machine shall mount upwardly, as more fully set out hereinbelow. The desired adjustment of the main planes 35 is materially aided by the proper manipulation of a horizontal rudder. By reason of the construction of this invention, which excludes a frame pivotally suspended from the main planes and arranged to be swung 40 either to the rear as stated, or to the front, it will be understood that the weight, carried low down by the suspended frame, will, when shifted to the rear by swinging the suspended frame rearwardly, tend to elevate 45 the forward edges of the main planes, while a forward movement of the weight brought about by swinging the suspended frame toward the front will tend to correspondingly depress the front edges of the 50 main frames and to elevate the back portions, thus inclining the planes for a downward movement of the whole.

In addition to the means provided for 55 swinging the weight forward or rearward for the purposes stated, it is an object of this

invention to support a platform upon the suspended frame, and at the lower part of the frame, to carry the weight, and the platform is arranged to be moved sidewise with respect to the suspended frame, and, at the same time to be moved backward or forward with the frame. The devices, usually hand-operated, for swinging the suspended frame include members borne by the platform and movable bodily with the sidewise movement of the platform, and the same may be stated regarding means for operating the horizontal rudder. Also, hand-operated devices are arranged upon the platform in easy reach of the operator and movable with the platform, for drawing the platform sidewise on the suspended frame, in order to place the weight promptly toward the ends of the main planes which become too greatly elevated by air disturbance or change of direction, and thus restore the planes to the desired horizontal position. A skilled operator will employ the movement of the suspended frame rearwardly, to enable him to bring the whole to rest upon the ground after flight, with the least practicable jar or shock.

The accompanying drawings forming a part of this application include Figure 1 which represents a side view of this invention in the position of normal, horizontal flight. Fig. 2 is a fragmentary side view showing the front of the main planes elevated. Fig. 3 is an enlarged side view of the lever carried by the platform and movably engaging the rectangular shaft, shown in section. The section of the platform is taken lengthwise through the slot that permits the lever to operate. Fig. 4 is a front view of this invention. Fig. 5 is a side view of the lever for moving the platform sidewise in either direction with respect to the suspended frame. The section of the platform and of the arm engaged by the lever is taken on the broken line $x-x$ of Fig. 7. Fig. 6 is an enlarged cross-section of one of the roller clips upon which the platform is carried. Fig. 7 is a plan view of the platform and parts carried thereby, taken from below the platform. Fig. 8 is a longitudinal section of one of the extensible shaft connections.

In the drawings and throughout the specification the same number is used to refer to the same part.

Considering the drawings, the principal portion 1 comprising the main planes, has the rigidly attached rearwardly-extending frame 2, provided with a horizontal rudder 3, operated by the tiller 4, to which the ends 5 and 6 of the steering cord are fastened. The cord passes around the grooved pulley 7, at the top of vertical shaft 8 carried by the planes, and the shaft includes two universal or ball joints 9 and 10 and an extensible joint 11, to allow for the sidewise and back and forth swing of the shaft as referred to hereinbelow. The shaft 8, and, consequently, the horizontal rudder 3, is operated by the hand lever 12, that engages the toothed quadrant 13, and is within convenient reach of the operator occupying seat 14 on the platform 15. The platform is carried by a frame pivotally suspended from the main planes and comprising the curved side supports or braces 16, 17 and 18, each connected with the planes by a ball joint such as the joint 19. Vertical rods such as the rods 20 and 21 form parts of the suspended frame on either side of the platform, and the rods pivotally support a carriage 22 upon which the whole rests when upon the ground.

The platform is easily moved sidewise by reason of the employment of roller-bearing clips such as shown in Fig. 6. The clip is marked 23, the roller is designated 24, and the front tube or rod of the lower portion of the suspended frame is referred to by the number 25. At the back, the suspended frame has a tube or rod 26 parallel with tube 25, and connecting the curved braces at the back.

Upon the platform 15 is a motor 27, that drives a vertical shaft 28, and the shaft includes the ball joints 29 and 30, and the shaft connection 31. As best illustrated in Fig. 8, the shaft 28 is divided within the connection 31, and one end of the shaft has a pin *a* engaging a longitudinal slot *b* in the connection. The other end of the shaft 28 is secured to the connection by means of the pin *c*. I do not limit my invention to any particular form of universal joint or extensible shaft connection. By means of the connection set out in Fig. 8, and, the connection 11 for the vertical shaft 8 is of like construction, the shafts may become lengthened or shortened as the platform swings or moves and still act to rotate the parts with which the shafts are engaged at their upper ends. At the top, the shaft 28 is provided with a suitably supported miter gear 32 by which the propeller 33 is driven.

To swing the suspended frame backward or forward, the platform carries the lever 34, the butt end of which has a roller-bearing connection with the transverse rectangular shaft 35, and the lever may be locked in any position by the engagement of the hand-

latch 36 and quadrant 37. As the platform 15 moves sidewise, the lever 34 moves with it, but, at any point the lever will turn the shaft 35 thus operating the arms 40 and 40^a. The ends of shaft 35 are rounded and supported in suitable hangers 39 carried by the side bars of the suspended frame. The rods 41 and 42, extend rearwardly and upwardly, and are pivotally connected with the rearwardly-extending frame 2. It is now thought to be made clear that by means of the lever 34 and connections described, the suspended frame may be swung backward or forward. If swung backward, the weight of the motor and operator, tending always to keep the suspending rods 20, 21 and their fellows, as well as the curved braces 16, 17, and 18 vertical, will throw up the front of the main planes as indicated in Fig. 2. Swinging the suspended frame to the front will have a contrary effect.

Now, considering especially, Figs. 5 and 7, it will be noted that the lever 43, provided with a hand latch in engagement with the toothed quadrant 44, has a lower rounded end 45 engaging one leg of a bell crank lever 46 by means of a slot 47 running lengthwise of the leg. The bell crank turns on the pivot 48, shown on the bottom of the platform 15 in Fig. 7, and the pivot is located at one side, but, about midway between the ends of the platform to afford an even pull. The remaining arm of the bell crank is marked 49, and it has a longitudinal slot 50 engaging a pin 51 projecting from a cross-bar 52 secured at its ends to the side bars 53 and 54 of the suspended frame. While the parts thus described constitute a simple and cheap contrivance for moving the platform sidewise, I do not limit myself to those parts or their construction as shown.

The operation of this invention may be explained as follows: Let it be assumed that the invention is flying forward, and moving with considerable velocity. Naturally, the effect of the air upon the body of the operator and upon all the weightier parts carried low upon the suspended frame below the main planes will be to retard the lower portion of the frame and turn the front edges of the main planes downwardly. The operator could rectify that depression by turning the front portion of his horizontal runner downwardly, but, only at the expense of his motor power and a decrease in his speed. By swinging his suspended frame rearwardly he accomplishes the same thing and presents no additional surface to the air through which he is rapidly passing. To direct this invention up or down quickly upon occasion, the operator may bring into play both the effect of his horizontal rudder and the swing of the suspended frame to displace his weight.

Whatever the position of the suspended

frame, it is believed to be made out clearly by the foregoing explanation that an excessive rise of the main planes at either right or left hand may be counteracted by moving the platform and, therefore, the weight to either side. In fact, the weight-shifting and rudder-operating mechanisms may all work together, or independently as desired.

I claim as my invention:

- 10 1. In an aeroplane, the combination with the main planes, of a rearwardly-extending frame rigidly attached to the main planes, a frame pivotally suspended from the main planes and arranged to be swung forward or rearward, a platform supported by the said suspended frame below the main planes and constructed to move sidewise on said frame, the said platform having a seat for the operator, means extending near to the seat for moving the platform sidewise on the said frame in either direction to balance the main planes, and means actuated by the operator for moving the said frame forward or rearward to depress or elevate the main planes.

- 20 2. In an aeroplane, the combination with main planes, of a rearwardly-extending frame rigidly attached to the said main planes, a frame pivotally suspended from the said main planes and arranged to be swung forward or rearward, a platform supported by the said suspended frame and movable sidewise thereon, hand-operated means for moving the said platform sidewise in either direction, a rod pivotally connected with the said rearwardly-extending frame, and means including hand-operated devices borne by the said platform and movable sidewise therewith whereby a force

may be exerted upon the said rod to elevate or depress the main planes.

3. In an aeroplane, the combination with the main planes, of a rearwardly-extending frame rigidly attached to the main planes, a frame pivotally suspended from the main planes and arranged to be swung forward or rearward, a platform supported by the said suspended frame below the main planes and constructed to move sidewise on said frame, a propeller carried by the main planes, a motor carried by the said platform, extensible power-transmitting devices provided with universal joints and connecting the motor and propeller, means actuated by the operator for moving the platform sidewise on the said frame in either direction to balance the main planes, and means actuated by the operator for moving the said frame forward or rearward to depress or elevate the main planes.

4. In an aeroplane, the combination with the main planes, of a frame pivotally suspended from the said planes and arranged to be swung forward or rearward, a platform supported by the suspended frame and movable sidewise thereon, hand-operated means for moving the said platform sidewise in either direction, and means connected with the said planes and with the said platform whereby the said suspended frame is swung forward or rearward and the said main planes depressed or elevated.

In testimony whereof I affix my signature in presence of two witnesses.

EDWARD H. WYMAN.
